Jacob Barley and John Sprinkle
Potters Patent

The schedule referred to in the seal is as follows: "Jacob Barley and John Sprinkle, inventors of a new and
useful invention in the name of the said Jacob Barley and John Sprinkle, to wit, the invention
of the improvement in the machine for threshing wheat and other grain."

To all to whom these presents shall come, Be it known that the said Jacob Barley and John Sprinkle
of the County of Rockingham and State of Virginia inventors of a new and
useful wheat and other grain threshing machine and that the following is a full and
exact description thereof. The improved threshing machine for threshing all kinds of
small grain as wheat, rye and oats also other grain off the stalk and out of the head.
consists of a threshing box, two open cylinders, two convergent auger shafts and pair of hand
wheel and pulleys. Figure A represents the threshing box consisting of four posts B, B.
B, B. the two front posts each four feet eight inches in height and four inches
square; the two back posts each four feet two inches in height and four inches
square, two side plank C, C, each six feet two inches in length, three inches thick, thirteen
inches in width, with a thickness three inches of the center of the notched having sixteen
figs from thence to the end, they are reduced to five inches from the lower edge, these
side plank C, C, are rabbeded out one inch when they come against the front posts B, B.
the front post may also be rabbeded out one inch; the back posts are rabbeded out one
inch so that they come against the plank C, C, that which may also be not large enough
to receive them, the side plank C, C, are fastened to the posts B, B. by the screws C, C, the two
hns G, G, are each four feet nine inches long, four by five inches square, these pieces
G, G, are framed into the front and back posts B, B, B, B, and a half inch from
the lower end with a tenon passing through the post seven eight inches in order to
receive the top G, G. The top plank represented by the letter H, is tenoned into the
front post B, B, with a mortise suitable to a tenon on the back post B, B, H, the
cabinet for the front threshing board to the spike cylinder Fig. I, H, the cabinet for the back
threshing board to the spike cylinder Fig. I, and front threshing board to the notched head cy-
linder Fig. J, the back board H, may be used to the spike cylinder Fig. I, when thresh-
ing grain the cleavage off the stalk, or it may be used as the front threshing board to the
notched head cylinder Fig. J, when threshing straw and out of the stalk. The back threshing board

to the notched bar cylinder Fig. 3 when threshing clover seed out of the clover. If you support
 said end under the timber it resting on the timber C. The two sides of this bar Fig. 1
 may be formed together by these pieces of timber each from a single square one piece planed
 through the back part 13. D. there are a half inches from the lower end; the other piece
 planed through the front part 13. B. twelve and a half inches from the lower end; the lower end
 the lower of these two pieces coming through five or six inches so as to receive the bar
 D. D. the a piece of timber formed in the two sides of blank A. A. between the two cylinders
 with a short piece not reaching through; and the bar may be drawn together by the screws
 & c. Fig 1 represents the spade cylinder which may be used for threshing clover seed off
 the stalks and all kinds of small grain as wheat &c. consists of three wooden boards of
 ten inches in diameter into which are let in four stones four & a half inches square which
 are held together in the middle by two iron rods 1. 2. and fastened to the stones to E.
 by means of four nuts, these may be either four or five round through each of the stones
 E. in order to prevent the stones from splitting. When drawing in the spade S. the boards
 are one inch and three fourths in length half inch by five eight square at the stone
 gradually tapering to one fourth by three eightths of an inch at the end. the spade in
 the concave Fig. 5 of the same dimensions which spade have a considerable bend in
 order that the stones may the more readily leave the cylinder when threshing the
 clover. Fig. 6. the iron band should placed on each end of the cylinder for the
 purpose of holding the stones C. in their places. Fig. 5 a piece of the spade cylinder
 Fig. 1. a piece of bound stones twelve and a half inches thick and may be bound
 from ten to twenty inches in width with a wooden band six inches in diameter and
 six wrought iron bars, from three eighth to five eighth of an inch thick and
 from an inch and a fourth to two inches in width, these bars are to be let in with in
 one fourth of an inch with the surface of the band, a inch thick that fourth is to be notched
 down the width of the band nearly level with the band so that when the bands
 are on the ends of the cylinder they will bind harder on the band than on the bars.
 these bars are held together in the middle of the cylinder Fig. 7. by the iron rods
 &c. these rods may be fastened to the band by wire or screws. these bars have each

or from one fourth to half an inch in depth standing in a concave position on one side. — swinging off the bars these notches may be cut square on both sides or irregular on one side and planing on the other side. Figure 4 a concave of the notched bar cylinder. Fig. 5 is a concave of the circular pieces b, b, of white oak timber, one or two and a half inches thick and three inches wide with one end fastened to the side plank d, of the top Fig. 6, by the screws a, a, the other end supported by the springs c, c, these circular pieces b, b, are lined with plank e, e, from one inch to one inch and a half thick on which are fastened plates a, with notches or grooves, these circular plank and circular plates are fastened to the circular pieces b, b, by the screws h, the springs c, c are fastened at one end under the timber f, with a diamond shaped pin passing through the eye of the same m, which screw passes through the timber f, to set the concave Fig. 4 in contact or position over the notched bar cylinder Fig. 3. Fig. 2 a log or board which rests on the pieces of timber P, P, which form a block square the outside piece P, P, resting in a hole or notch in the block held by the screws i, the inside piece is a ballast or flat tree which when it comes against the post P, P, the post P, P, is also an obstacle out-tree in order to make the piece come with the post on both sides so as to be out of the way of the concave Fig. 4, the pieces P, P, are held together by the screws a, a, the pieces may properly be called a sliding head block, which is held to its place by the top displaced on the front side of the front post P, P, when touching with the spike cylinder Fig. 1 and the top d, must be placed on the back side of the front post P, P, when the head block is moved so that the cog wheel Fig. D will gear in the spur of the notched bar cylinder Fig. 3. The cylinder Fig. 1 is one 3. may be varied from eight to sixteen inches in diameter to three feet in length. The number of spikes in the spike cylinder Fig. 1 may be varied from twenty four to seventy five according to the length of the cylinder and the number of spikes may be varied from two to six. The number of bars in the notched bar cylinder Fig. 3 may be varied from six to eighteen. It is said to the thickness top. It is said that both the bars together in the middle of the spike cylinder. It is said that fasten one end of the concave of the notched bar cylinder to the side plank of the top g, wrought iron bar of the notched bar cylinder. What are called as an even concave in the above described a flat and even and this being practice was followed to art. First the plan of working two cylinders in one by means of a sliding head block.

Block secundaria is to work with the cylinder by means of moving a band which is
secondarily. The improvement of making an open cylinder by means of which it is
rendered about one half lighter and the dispensing with about two thirds of the spikes
formerly used in the common spike machines. It also claims the invention of
using one end instead of straight spikes as here is used in threshing machines.

Thirdly, The selected bar cylinder as claim is an invention in itself.

13, 14, part to the thresh bag. 6. timbers framing the front and back part to
gather at the lower ends. 13, 14, 15. timbers framing the bag together
also the bags. 16. stones in the spike cylinder. 17. blocks that hold the spring
down. 18. timber that holds the ends of the springs. 19. timber framed into
the side plank between the two cylinders. 20. side plank of the thresh bag
21. stones that hold the groove cast iron plates and the circular plank
on the circular pieces 22, 23, 24 back slats board to the notch back cylinder
25. back slats board to the spike cylinder and front slats board to the notch
back cylinder. 26. blocks that hold the notched back together in the middle of the cyl
inders. 27. sliding head block on which the auger hand wheel rests. 28. front slats
board to the spike cylinder. 29. spikes in the cylinder and concave. 30. circular
foot board. 31. screw that holds the timber on sliding head block together and
which the auger hand wheel rests. 32. circular pieces on which the circular
plank and groove cast iron plates are secured. 33. bag that holds the sliding
head block to its place when threshing with either cylinder. 34. springs on
which the concave rests. 35. screws that hold the side plank to the front, also
the blocks with a notched back the sliding head block moves. 36. spring
stones. 37. circular plank under the groove cast iron plates. 38. groove
cast iron plates. 39. large screw that holds the thresh bag together between
the cylinders.
